ANATOMIC SPLINT

Roger Anderson, Seattle, Wash.

Application: October 10, 1933, Serial No. 692,929

14 Claims. (Cl. 128—85)

This invention relates to fracture reducing splints and it has reference more particularly to splints designed for reduction of fractures of the arms; it being the principal object of this invention to provide a substantial, light weight, easily manipulated and quickly adjustable splint, designed primarily for fracture reduction by direct skeletal attachment, and wherein provision is made for relative rotation and angular adjustment of the traction devices and for the mechanical application of traction to a desired amount.

Another object of the invention is to provide an improved form of traction pin designed for a partial or limited piercing of a bone in the reduction of forearm fractures.

Another object resides in the construction of parts adapted to be used interchangeably on the main frame structure to adapt the splint to leg or to arm fractures.

Still further objects of the invention reside in the details of construction and in the combination of parts of the splint and in their mode of operation, as will hereinafter be fully described. In accomplishing the different objects of the invention, I have provided the improved details of construction, the preferred forms of which are illustrated in the accompanying drawings wherein—

Fig. 1 is a plan view of a fracture reducing splint embodied by the present invention, especially for forearm fractures.

Fig. 2 is a side view of the same.

Fig. 3 is an enlarged sectional detail of a traction yoke base as used in the arm splint.

Fig. 4 is a cross section on the line 4—4 in Fig. 1.

Fig. 5 is a perspective view of the improved form of traction pin for limited piercing of the skeletal parts and a retaining pad used therewith.

Fig. 6 is a perspective view of the arm splint showing the traction yokes adjusted to positions at right angles to each other.

Fig. 7 is a plan view of the splint as applied for reduction of a fracture in the forearm.

Fig. 8 is a view of an alternative form of yoke and yoke support disposed laterally of the frame.

Fig. 9 is a cross section on line 9—9 in Fig. 8.

Fig. 10 is a cross section on line 10—10 in Fig. 8. Referring more in detail to the drawings—

In a preferred form of construction the splint comprises a rectangular base frame structure made up of transversely disposed, opposite end bars 1 and 2 joined rigidly in spaced relation by

four longitudinal rods 3 arranged in pairs at opposite sides of the frame. The rods of each pair are vertically spaced and are parallel to each other and the two pairs of rods also are parallel for adjustment therealong of a cross bar 4 that is mounted at its ends on the pairs of rods for slidable adjustment in a direction longitudinally of the frame.

To adapt the device for reduction of arm fractures especially, brackets 5 and 6 are attached to the end bar 2 and to the cross bar 4 respectively, by bolts 5a and 6a. These brackets are curved upwardly and away from each other and are provided at their upper ends with bearing portions 7 formed with conical sockets 8 as seen in Fig. 3, opening to their inner faces. Mounted in the bearing portions 7 are base members or guides 9 by which the traction yokes 10 are supported for adjustment.

As seen in Fig. 3, each of the base members 9 is formed with a conical lug 12 adapted to seat rotatably in the socket 8 of its mounting member 7 and a bolt 15 is extended through an opening 16 in the bearing and is threaded axially into the conical lug 12 in a manner whereby tightening of the bolt by means of a cross pin 15a at its outer end will draw the associated parts tightly together and will thereby hold the base member 9 at any set position of adjustment. Loosening of the bolt permits the base member 30 to be rotatably adjusted to change the relative positions of the two yokes. For example they may be rotatably adjusted from relative right angular positions as in Fig. 6 to any position intermediate that at which they are both in the same plane, as seen in Fig. 2. Also, each of the bases or yoke mountings 9 is formed with spaced flanges 17 and 17' between which the flat base portions 10a of the traction yokes are contained.

The yokes are of U-form and the positions of the supports in which they are mounted are such that the yokes open toward each other, as seen best in Figs. 1 and 6. The flat base portions of the yokes are evenly and arcuately curved and are held adjustably between the flanges 17—17' of the base members for lateral adjustment. The outer edge of the base of the yoke is guided by seating against a pair of rollers 18—18', symmetrically spaced at opposite sides of the axis of the mounting piece and the inner edge is engaged by a roller 19 located in the axial line, thereby to hold the yoke steady and securely, but permitting it to be laterally adjusted in either direction between the flanges and the rollers. A bolt 20 extends through the 55

flanges for mounting the roller 19 and this bolt is provided with a wing nut at one end which may be tightened on the bolt to clamp the flanges tightly against the yoke to hold it at any set position of adjustment.

Each yoke is provided at the ends of its arms with transverse aligned slots 25 for seating the ends of a cross rod 26, as illustrated at the right hand side in Fig. 1 and Fig. 6, or to receive a traction pin 27 and stem of a retaining pad 28 as seen at the opposite end of the frame. Also there are set screws 29 threaded into the end portions of the yokes in a manner to be tightened against the ends of the rod or against the pin or stem of the pad to hold them securely in the yoke arms. The cross rod 26 when applied through the bone of the arm, as seen in Fig. 7, and seated in the notches of the yoke arms, may serve as an anchor or as a member for direct application of skeletal counter traction. The traction pin 27 mounted by one arm of the opposite yoke is pointed at its end and is intended to pierce the limb only to a limited extent as permitted by a stop collar 30 that is fixed on the pin at a definite distance from its pointed end. There is also a flange 31 on the pin engageable with the inner face of the yoke arm to prevent slippage in the yoke of the pin under pressure and this is square or irregular in shape to prevent its rotating when enclosed in the cast.

The short pin 27 is used for setting lower arm fractures where it is essential that it pierce the radius to a limited extent just sufficient to provide the necessary holding traction and it is limited in its extent of piercing by the collar 30. A stem 32 extends from the base of the U-shaped member and may be clamped in the yoke arm opposite that which supports the traction pin. The purpose of this pad applied opposite the traction splint is to support the arm against slipping from the pin and the pin will then retain its holding connection with the bone to which it is partially applied.

The cross bar 4 is mechanically adjusted along the frame structure by means of an adjusting screw 40 that extends revolvably through an opening in the cross bar 4 and is threaded through a lug 42 on the under side of the cross bar 4. This shaft has a hand wheel 44 fixed to its outer end for turning it, and it also has a nut 45 threaded thereon and fitted against the outer face of the cross bar 4, as seen in Fig. 2.

Assuming the device to be so constructed, in using it for the reduction of a fracture of the forearm it is applied as illustrated in Fig. 7. First the counter traction rod 26 is extended through the enlarged upper end of the ulna near the tip of the olecranon and the ends of the rod are then applied to and secured by the set screws 29 within the arms of the yoke at one end of the frame supported by bracket 5. The traction pin 27 is inserted through the center of the radius from its lateral aspect about two fingers' breadth superior to the tip of the styloid process, and is forced in until limited by the stop collar 32; the pin 27 and the pad 33 then being applied to the opposite arms of the yoke supported by bracket 6, at the other end of the frame. To reduce the fracture and properly set the bones, the two yokes may then be rotatably adjusted relative to each other to bring the fractured bones into proper relationship for reducing the fracture and traction may be applied by rotation of the adjusting screw 40 to adjust the yokes apart to effect the lateral adjustment.

After sufficient traction has been applied to bring the fractured bones into position for setting, a cast or splint may then be applied about the arm and allowed to set.

While it is not desirable nor necessary in the ordinary use of splints of this character using skeletal traction to provide for partial transfixion of a bone, it is necessary in the successful reduction of forearm fractures by reason of the complex anatomy of the forearm. While the ulna is the larger of the two bones in the upper forearm, it is the smaller at the wrist and it is very undesirable that the smaller ends of either the ulna or the radius should be pierced by the traction rod or pin by reason of the close relation of the nerves and the blood vessels of these parts. Furthermore, the fact that the radius alone articulates at the wrist and projects beyond the ulna has important clinical significance. It is rather inexplicable that other skeletal methods have entirely omitted consideration of the fact that in rotation of the forearm the radius moves, while the ulna remains stationary. For example, when the forearm is in supination, as shown in Fig. 7, the bones thereof are substantially parallel, but incident to rotation of the hand to pronation the radius rotates about the pivot connection with the humerus through an angle of approximately one hundred and eighty degrees, and across over the ulna which remains stationary.

It should be apparent that by reason of this relative movement of the bones, it would be impossible to transfix both bones with a pin and still be able to obtain any rotation of the fractured portions of a bone. In fact, a pin extended through both bones would be an effective lock against rotation and this would be contrary to the principle of the present device.

The anatomical axis of rotation of the radius about the ulna is coincident with a straight line through the styloid process of the ulna and a point substantially intermediate the points of connection of the radius and ulna with the humerus. This anatomical axis of rotation is designated by the dotted line in Fig. 7, and it is the intention that when a forearm is applied to the splint its anatomical axis will be disposed in coincidence with the axial line of rotation of the two yokes which is along a straight line through their mounting axes. The proper disposition of the forearm when applied to the yoke, as in Fig. 7, is obtained by placing it centrally between the arms of the yoke which mounts the pin 26 and then so locating the stop collars 30 and 31 on the pin 27 that when the collar 31 engages the yoke arm, the collar 30 will locate the arm at a position somewhat off center so that the styloid process of the ulna will be centrally located in the yoke.

A hand supporting bracket 46 is adjustably attached by a bolt 47 to the base 7 at one end of the frame, as seen in Fig. 2, upon which the palm of the hand may rest if it is desired that the arm be retained in the splint for any length of time.

In Fig. 8 I have illustrated an alternative form of yoke and yoke support which better adapts the splint to the setting of fractures of the upper arm, or for the leg. For application of this yoke, the bracket 5 would be removed from cross bar 2 and the bracket 55 fixed to the cross bar 2 by the bolts 55a to extend to the side of the frame. This bracket 55 is equipped with a yoke mounting 9' like the mounting 9 already described, and this mounts a yoke 56 that is arranged to open lat-

erally with respect to the frame. The yoke 58 as is herein illustrated, conforms to that of my copending application Serial No. 669,703, both in manner of adjustment and in the manner of mounting the rod or traction wire 28' therein. When using yokes in this type of mounting, the arm is applied thereto substantially in the same manner as already described in connection with yoke 10 and rod 26 and adjustment is made in the same manner for the reduction of the fracture. The advantage in use of this laterally opening yoke and lateral bracket is that there is no interference by the supporting bracket to extending the elbow straight beyond the yoke as there would be in use of the device of Fig. 1.

After the fracture has been set, and after the plaster cast applied thereto has set, then the arm may be removed from the splint. When it is removed, the pin or rod 26 and also the pin 27 and pad 33 are left in place, and in this way effectively anchor the arm relative to the cast.

Splints of the various types above described for arm fractures, are easily and readily applied for reduction of fractures and provide for direct application of skeletal traction to any extent desired. They also provide for rotative adjustment of the yokes while attached to the limb so as to bring the fractured bones into proper position. The fact that the brackets are detachable permits easy and quick replacement of one type with the other to adapt the device to leg or arm fractures.

Having thus described my invention, what I claim as new therein and desire to secure by Letters Patent is—

1. In a traction splint, a base structure, a pair of traction yokes, supports for said yokes whereby they are held in positions opening toward each other, said supports being mounted in the base structure in axial alinement and rotatably adjustable relative to each other about their axes, means mounted by each yoke for effecting skeletal attachment to a limb applied thereto, means for adjusting the spacing of said yokes for applying traction to the limb and means for fixing the position of adjustment of the yokes about their axes.

2. In a traction splint, a base frame, brackets fixed thereto, yoke mounting bases rotatably adjustable in said brackets in axial alinement, traction yokes of U-shaped form mounted in said bases and opening toward each other, means removably applied to the yokes across their open ends for effecting holding connection with a skeletal part of a limb applied within the yokes; said yokes having arcuately curved base portions mounted slidably in guides of their respective mounting bases, thereby to permit change in the angular relationship of the yokes relative to the axial line about which they are rotatably adjustable.

3. In a splint of the character described, a pair of traction yokes adapted to embrace the forearm at points below the elbow and above the wrist, respectively; the first of said yokes mounting a traction pin across the mouth thereof for transfixing the ulna; the other yoke mounting a pin in one arm thereof for partial transfixion of the radius and a pad in the other to support the arm and hold the radius against displacement from the pin, and means mounting the said pair of yokes to permit relative rotation thereof about the anatomical axis of the forearm.

4. In a splint of the character described, a supporting frame, and a pair of spaced traction

means mounted on the frame and relatively rotatable about a common axial line, said means being adapted to be applied to the forearm at points below the elbow and above the wrist, respectively, and one of said means mounting a pin rigidly therein for transfixion limited to the distal radius and having stops thereon to determine the position of the arm relative to the splint and whereby the arm will be located with its anatomical axis coincident with the common axis of rotation of the traction means.

5. A traction splint comprising a base frame structure, a bracket attached to the frame at one end, a cross bar adjustable along the frame between its opposite ends, a bracket fixed on the cross bar, yoke mounting bases mounted rotatably in axial alinement on the brackets, traction yokes mounted by the said bases, means supported by the yoke arms for effecting skeletal attachment to a limb applied to the splint, and a hand screw connecting the frame and cross bar whereby the latter may be adjusted for the application of traction to the limb.

6. A traction splint comprising a base frame structure having opposite end bars and longitudinal rods connecting the end bars, a cross bar mounted on and slidably adjustable along the longitudinal rods, a bracket fixed on the cross bar, a bracket fixed on one of the end bars, yoke mounting bases supported by the brackets, traction yokes adjustably mounted by the bases and opening toward each other, devices removably applied to the arms across the open ends of the yokes for effecting skeletal attachment to a limb applied thereto, and a hand screw extended rotatably through an end bar of the frame and threaded into the cross bar whereby the latter may be adjusted to increase or decrease the spacing of the yokes; said yokes being laterally adjustable in the bases and said bases being rotatably adjustable in their supporting brackets about a common axial line.

7. In a traction splint, the combination with a support, of a yoke applied thereto having opposite side arms provided with passages at their ends, a traction pin removably applicable to the passage of one arm to extend into the yoke mouth, means on the pin for limiting its extent of piercing a skeletal part of a limb applied to the yoke, releasable means for holding the pin in the yoke arm, a pad having a mounting stem applied to the opposite arm of the yoke and having parts for embracing the limb to retain it against displacement from the traction pin and releasable means for holding the pad at different positions of adjustment relative to the arm.

8. In a splint for the reduction of forearm fractures, means for holding the upper forearm for the reduction of a fracture, and a reduction means associated therewith and including a transfixion pin rigidly supported from the said reduction means for transfixing the distal radius for reduction of the fracture thereby and without extending beyond the transfixed fragment; said holding means and said reduction means being relatively rotatable about the anatomical axis of the arm, as applied to the splint, and adjustably mounted for change in their spaced relation.

9. A splint for the reduction of forearm fractures comprising a support, spaced reduction devices, means mounting said devices on the support whereby they are relatively rotatable about a common axial line, a transfixion means associated with one of the reduction devices for transfixing the upper end of the ulna, a trans-

fixion pin fixedly mounted by the other of said traction devices for transfixing the distal radius for manipulation thereof by movements of the traction device, and without extending therebeyond, and a means for changing the spacing of said traction devices.

10. A splint for the reduction of forearm fractures, comprising a supporting base, spaced reduction devices mounted on said supporting base, and relatively rotatable about a common axial line, means associated with one of the said reduction devices for transfixing the upper end of the ulna, a transfixion pin with one end rigidly fixed in the other of said reduction devices and extending therefrom for transfixing the distal radius near its styloid process, without extending therebeyond; said transfixion means of the two reduction devices being so mounted and so designed as to support an arm applied thereto in position that its anatomical axis through the styloid process of the ulna will coincide with the longitudinal axis of the splint about which said reduction devices are rotatable; and an adjusting means for one of the reduction devices for varying the spacing of said reduction devices on the supporting base.

11. A splint for the reduction of forearm fractures comprising a supporting base, a pair of adjustably spaced reduction devices, means fixedly mounting said devices on the base for relative rotation thereof about a common axial line and permitting independent adjustment in angular position relative to the said axis, means mounted by one of said devices for transfixing the arm through the upper portion of the ulna, a transfixion pin fixedly mounted by the other of said

devices, for a partial transfixion of the arm, confined to the radius and adapted for entering the radius near the styloid process from the lateral aspect, and having a transfixion limiting shoulder thereon, and means operable for adjusting the spacing of the reduction devices for effecting extension and reduction of the fracture.

12. A method of treating forearm fractures, comprising supporting the upper forearm for reduction, applying a transfixion means to the distal fragment of the radius in a manner not to extend substantially beyond the cortex opposite that to which it is first applied, applying the said transfixion means to an external splint, and then effecting reduction by manipulation of the splint.

13. A method of reducing forearm fractures, comprising securing the upper forearm by skeletal attachment means to an external splint in a manner suitable for reduction, applying a rigid transfixion means to the distal fragment of the radius from the lateral aspect and to such extent that it does not extend substantially beyond the opposite cortex, fixedly mounting the transfixion means in an adjustably fixed part of the splint, then reducing the fracture by changing the position of the said adjustable part of the splint relative to the upper arm mounting.

14. A method of treating forearm fractures, comprising holding the upper forearm for treatment and applying a rigid transfixion member to the distal fragment of the radius in such manner that it does not extend substantially beyond the opposite cortex, then reducing the fracture and finally anchoring the transfixion means to retain the reduction and effect immobilization.

ROGER ANDERSON.
